COOLING UNIT FOR SEMICONDUCTOR DEVICES OR THE LIKE

Thomas D. Coe, Winchester, Mass., assignor to Wakefield Engineering, Inc., Wakefield, Mass., a corporation of Massachusetts

Filed June 15, 1961, Ser. No. 65,602

Term of patent 14 years

(Cl. D62—4)

FIG. 1 is a perspective view of a cooling unit for semiconductor devices or the like showing my new design;

FIG. 2 is a side elevational view taken from the left of FIG. 1;

FIG. 3 is a side elevational view taken from the right of FIG. 1; and

FIG. 4 is a rear elevation view thereof.

I claim:

The ornamental design for a cooling unit for semiconductor devices or the like, as shown.
